VACUUM CLEANER

Erik Gustaf Ahnström, Stockholm, Sweden, assignor to Electrolux Corporation, Dover, Del., a corporation of Delaware

Application October 24, 1933, Serial No. 694,978
In Germany April 15, 1933

10 Claims.

(Cl. 15—16)

My invention relates to vacuum cleaners generally and more particularly to vacuum cleaners of the type having a cylindrical casing adapted to be mounted substantially horizontally above a surface. This casing encloses a dust bag and a motor-fan unit. The motor-fan unit has heretofore been advantageously supported within the casing by means of a ring of electrically insulating material bolted to the casing. The holes required to receive the bolts necessarily structurally weaken the ring.

One of the objects of my invention is to provide simplified means for securing the ring to the casing, which means does away with the necessity of forming holes through the ring. Thus, the ring is strengthened or a ring of the same strength may be made with smaller dimensions.

Another object of my invention is to do away with the necessity of having a complete ring and to use in place thereof segments of a ring.

A still further object of my invention is to secure the ring, or the segments of the ring, in place by clamping it between other parts of the casing, thus obviating the bolts formerly used.

Another object is to secure a fan housing in place by the same clamping means employed to hold the ring or segments thereof.

Further objects and advantages of my invention will be apparent from the following description considered in connection with the accompanying drawings, which form a part of this specification and on which:

Fig. 1 is a side view, chiefly in cross-section, of a preferred embodiment of my invention;

Fig. 2 is an end view of the device shown in Fig. 1 with certain of the parts removed;

Fig. 3 is a cross-sectional view, on an enlarged scale, taken on the line 3—3 of Fig. 2;

Fig. 4 is a cross-sectional view, on an enlarged scale, taken on the line 4—4 of Fig. 2;

Fig. 5 is a cross-sectional view, on an enlarged scale, taken on the line 5—5 of Fig. 2;

Fig. 6 is a cross-sectional view, taken on the line 6—6 of Fig. 4;

Fig. 7 is a view similar to Fig. 2, but showing another embodiment of my invention; and

Fig. 8 is a cross-sectional view, on an enlarged scale, taken on the line 8—8 of Fig. 7.

Referring more particularly to Fig. 1, reference character 10 designates a cylindrical barrel forming a portion of a casing. Suitably secured to one end of barrel 10 is a ring 11. A closure member 12 is adapted to be clamped onto ring 11 by means of spring clips 13 or the like. Mem-

ber 12 is provided with a threaded central aperture 14 which receives a hollow coupling member 15. A flexible hose 16 is adapted to have one end secured to coupling 15 and the other end secured to a suitable suction nozzle 17. A rigid hollow handle 18 may be interposed between hose 16 and nozzle 17.

Suitably secured to the other end of barrel 10, as by rivets 20 or the like (Figs. 3 and 4), and forming part of the barrel, is a ring 19 provided with an inwardly extending annular shoulder 21. Ring 19 is formed with a plurality of wedge-shaped recesses 22. In the embodiment disclosed there are four of these recesses distributed equi-distantly around the ring. Located within each recess 22 is a wedge-shaped foot or supporting member 23 preferably made of rigid electrical insulating material, such as "bakelite" or the like. Members 23 are provided with recesses 24 into which pins 25 extend from one side of the member. These pins may be cast in the members 23, or otherwise suitably secured thereto. Pins 25 serve to support springs 26 having spiral portions 27 of increasing radius and straight portions 28. Straight portions 28 are secured by means of bolts 29 to the frame of an electric motor 30. Motor 30 is thus supported resiliently through springs 26 by supporting members 23, the springs comprising resilient support members for the motor.

Motor 30 is provided with an armature shaft 31 upon which is mounted one or more fan rotors 32 and 33. Rotor 33 is enclosed within an inner housing 34 comprising a cylindrical portion 35 and an end wall portion 36. Wall portion 36 is provided with a central aperture 36a. The other end of cylindrical portion 35 is formed with an outwardly extending radial flange 37 which overlaps shoulder 21 on ring 19 and is clamped between shoulder 21 and supporting members 23 (Fig. 5) when the latter are clamped in position, as will be explained later. A packing ring 38 may be located between shoulder 21 and flange 37 in order to provide a substantially air-tight joint.

A transverse wall 39 is secured within barrel 10 ahead of rotor 32 and is provided with a central opening 40 protected by a perforated plate 41. A dust bag 42 made of material which readily permits air to pass therethrough but which prevents the passage therethrough of dust is located in the space within barrel 10 ahead of wall 39. Dust bag 42 is secured to a ring 43 provided with an outwardly extending flange 44 which is

adapted to be clamped between ring 11 and closure member 12.

An end member 45 is secured to ring 19 by means of a plurality of stud bolts 46. Member 45 is formed with an outwardly extending flange 47 which is provided with apertures to receive bolts 46. Flange 47 extends radially inwardly beyond ring 19 so as to contact supporting members 23, as clearly appears in Figs. 4 and 5. Thus, when bolts 46 are tightened, flange 47 is drawn against members 23 and forces them against flange 37 on fan housing 34, which in turn is pressed against packing ring 38 which abuts against shoulder 21. In this manner bolts 46 serve to hold in place the end member 45, supporting members 23 and fan housing 34, the supporting members and the fan housing being clamped between the end member and barrel 10. Heretofore, separate fastening means have been required for each of these three members.

End member 45 is formed with a centrally threaded aperture 48 having threads similar to those in opening 14 so as to be able to receive coupling 15 when it is desired to use the device as a blower. Inclined louvers 49 are located adjacent to openings 48 and serve to direct air upwardly.

The unit is supported by means of a pair of runners 50 secured to rings 11 and 19. A handle 51 is provided for carrying the unit. A combined attachment plug and switch 52 serves for the supply and control, respectively, of electricity to the motor. A sealing ring 53 of soft rubber or other suitable material may be carried by motor 30 to prevent the passage of air between the motor and the casing, thus causing all of the air to flow through the motor in order to most efficiently cool the latter.

The operation of the device is as follows:

Rotation of fan rotors 32 and 33 by motor 30 cause a current of air to be drawn in through nozzle 17, hollow handle 18, hose 16, coupling 15 and opening 14 into dust bag 42. If the nozzle 17 is passed over a dusty surface, dust is drawn in with this air and is deposited within the dust bag, while the air passes through the material thereof to the fan. From the fan the air is discharged through motor 30, thereby cooling the latter, and is discharged from the unit through opening 48. The operation of the motor-fan unit sets up certain vibrations which are absorbed by the springs 26 and thus prevented from reaching the casing. In the event that any of the electric wires of the motor becomes grounded on the motor frame, current is prevented from reaching the casing because of the fact that supporting members 23 are made of electrical insulating material.

In the modification shown in Figs. 7 and 8, supporting members 23 are replaced by a complete ring 60. Ring 60 fits closely within ring 19 which is formed with an annular recess 61 in place of the wedge-shaped recesses 22. Flange 47 on end member 45 bears against ring 60 and forces it against flange 37 on fan housing 34. Flange 37 is thus forced against packing ring 38 which abuts against shoulder 21 on ring 19. A dowel pin 62 is provided between rings 19 and 60 in order to prevent relative rotation of the two rings.

Tightening of bolts 46 serves to secure end member 45, supporting ring 60 and fan housing 34 in place, the bolts thus performing the functions heretofore performed by three separate fastening means.

In the appended claims the term "casing" is

used to define some or all of the casing parts.

While I have shown two more or less specific embodiments of my invention, it is to be understood that modifications thereof fall within its scope which is to be limited only by the appended 5 claims, viewed in the light of the prior art.

What I claim is:

1. In a suction cleaner, a casing, an end member for said casing, and means for supporting an element in said casing in a manner to permit ready removal of the same by detachment of said end member, said last mentioned means including supports spaced about the element to be supported, and means on said casing cooperating with said supports for maintaining said supports 15 in a definite position, said end member constituting means for maintaining the parts in assembled relation.

2. In a suction cleaner, a casing, an end member an insulating ring between said end member and said casing and serving to connect said casing and end member but maintaining them in spaced relation, supporting means in said ring, said supporting means and ring being provided with complementary portions whereby the parts 25 are relatively fixed when the parts are assembled permitting ready removal of the supporting means when the end member is removed, said end member constituting means for maintaining the parts in assembled relation. 30

3. A suction cleaner including a casing, a ring forming an extension of said casing, a supporting element slidably receivable within said ring, an element to be supported, connecting means between said supporting element and said element to be supported, an end member for closing the end of the casing, and means for clamping said end member to said ring, said end member being constructed also to clamp said supporting element in place in said ring. 35

4. A suction cleaner comprising a casing, a ring forming an extension of said casing, a motor support slidably mounted within said ring, a motor, resilient means connecting said motor support and the motor whereby vibrations of the 45 motor are absorbed and prevented from reaching the casing, an end member for closing the end of the casing, and means for clamping said end member to said ring, said end member being constructed also to clamp said motor support in 50 said ring.

5. A suction cleaner including a casing, a ring forming an extension of said casing, said ring having a plurality of slots extending axially thereof, blocks inserted in said slots for supporting a motor, an end member for closing the end 55 of said casing, and means for clamping said end member to said ring, said end member being constructed also to clamp said motor supporting blocks in place. 60

6. In a suction cleaner, a casing including a barrel portion and a closure member for one end of said barrel portion, said barrel portion having internal recesses extending inwardly from one end of the same, motor supporting blocks 65 in said recesses, and means for securing said closure member to said barrel portion against the end of said supporting blocks and clampingly securing said blocks in said recesses.

7. A vacuum cleaner including a casing having 70 a ring forming an extension of said casing, said ring having a plurality of slots extending inwardly thereof, blocks of electrical insulating material inserted in said slots for supporting a motor insulated with respect to the casing, an 75

end member for closing the end of said casing, and means for clamping said end member to said ring, said end member being constructed also to clamp said motor supporting blocks in place.

5 8. In a suction cleaner a casing, motor supporting means attached to said casing and comprising a ring having an inwardly directed flange, said ring being provided with recesses on its interior, supporting members in said recesses and 10 abutting said flange, and a cover member for said motor connected to said ring on the side opposite said flange and clamping the supports in place.

9. In a suction cleaner a casing, a motor, means 15 for supporting said motor in said casing comprising supporting elements between said motor and casing spaced transversely of the casing, and an end member for one end of the casing, the construction and arrangement being such that

the supports are positively clamped between the casing and the end member and are prevented from moving axially of the casing, said casing being provided with means for preventing rotation of the supports about the axis of the casing. 5

10. In a suction cleaner, a casing including a barrel portion and a closure member for one end of said barrel portion, said barrel portion being provided with an internal recess extending inwardly from one end of the same, a rigid supporting member in said recess, a motor in said casing, means for supporting said motor from said supporting member, and means for securing said closure member to the end of said barrel portion against the end of said supporting 10 member in a manner to clamp the same in said recess. 15
